HEAT INTERCHANGE APPARATUS

Robert E. Kaestner, Baltimore, Md., assignor to
 E. A. Kaestner Company, a corporation of
 Maryland

Application July 30, 1934, Serial No. 737,658

3 Claims. (Cl. 257—108)

This invention relates to heat-interchange apparatus and has special reference to devices employed in heating, holding, cooling and storing liquids, and more particularly milk, cream, ice cream mixes and other dairy products during pasteurization, cooling and in storage.

Among the objects of this invention is to provide a simple, highly efficient and inexpensive means for overcoming the objections in devices heretofore used for such treatment of milk, cream, ice cream mixes, etc.

More specifically it is an object of this invention to provide a highly efficient heat-transfer construction between the hollow coil portion through which the cooling medium is passed and the interior of the vessel containing the liquid to be cooled.

Other, further and more specific objects of this invention will be readily apparent to persons skilled in the art from a consideration of the following description when taken in conjunction with the accompanying drawing wherein:

Fig. 1 is a substantially central, vertical cross-section of my new apparatus.

Fig. 2 is a section along line 2—2 of Fig. 1.

Fig. 3 is a fragmental, sectional view showing the heat-conducting union between the coils and the inner vessel.

Fig. 4 is a fragmental, perspective view showing the connections between the coils and the headers or manifolds which are used for supplying cooling fluid to the coils and receiving the fluid after it has passed through the coils and performed its service.

The apparatus comprises an inner tank or vessel 1 disposed within the outer vessel 2 in spaced relation thereto both laterally and at the bottom, the outer vessel 2 thus serving as a jacket. The vessel 2 is supported upon the legs 3 which are preferably adjustable to admit of raising or lowering the vessel 2.

A plurality of hollow coils 4 are secured to the vessel 1, preferably on the outside, and each coil is connected to and communicates at one end with a header or manifold 5 through which cooling fluid is supplied to the coils, and at the other end with the header or manifold 6 which receives the fluid from the coils after the fluid has passed therethrough and has rendered service as a cooling medium.

A special feature of my invention consists in using a plurality of these coils instead of a single coil so that the incoming cooling fluid will be supplied from the manifold 5 to the coils 4 at a plurality of elevations instead of only at the bot-

tom, as in prior devices of this kind. By this means, I obtain a more satisfactory distribution and more uniform cooling of the material within the vessel 1 and also great reduction of the head pressure of the cooling fluid. Ordinarily, I provide all of the coils with the same number of convolutions, but the number of convolutions need not be uniform in each coil and satisfactory results may be obtained by having one or more coils with a different number of convolutions than other coils.

These coils are positioned so that there is direct contact of the convolutions of the coils with each other and with the vessel 1. I have found this arrangement gives more satisfactory heat-transfer. As a further means of adding to the efficiency of heat-transfer, I fill the interstices between adjacent convolutions of the coils and the inner vessel 1 with a suitable heat-conducting material, and I have found solder an excellent material for this purpose. The solder secures the coils to the vessel 1 and also fills the interstices, thus forming a direct and voidless heat-transfer structure and union between the contents of the coils and the contents of the inner vessel.

My apparatus is provided with a perforated steam pipe 7, which extends into the lower portion of the space between the vessels 1 and 2 and is preferably disposed between the bottom 8 of the inner vessel 1 and the bottom 9 of the outer vessel 2. The apparatus also has an agitator or stirrer 10 which is supported by the cover 11 of the inner vessel 1 and is operated by a reduction geared motor 12 through the shaft 13. The motor is carried on a bracket 14 which in turn is supported to swivel on the bracket 15. The motor 12 may thus be swung into or out of operating position relative to the shaft 13.

Water is supplied to the water jacket consisting of the space between the vessels 1 and 2 through the pipe 16. This water jacket is closed at the top by the cover 17 tightly secured to and extending from the inner vessel 1 to the outer vessel 2. The cover 11 for the inner vessel 1 is preferably hinged at 18 to afford access to the interior of this vessel. However, the entire cover 11 may be easily removed, and the device thus lends itself to ready cleaning in order to meet the requirements of sanitation in the treatment of liquids such as milk. One or more thermometers 19 are also provided for ascertaining the temperature of the contents within the vessel 1.

This vessel 1 is also provided with an outlet plug valve 20 which is operated through the arm 21 and the lever 22. This lever 22 is pivoted at 23 and connects with the swinging arm 24 which has the threaded washer 25 and the nut 26. By pulling the arm 24 downward, the plug valve 20 is raised and liquid in the inner vessel 1 will flow out through the pipe 27 which also projects through the bottom 9 of the outer vessel 2. The plug valve 20 may be held in open position by swinging the arm 24 so as to bring the washer 25 below the bifurcated bracket 28 and moving the arm 24 into engagement with the bifurcated portion of this bracket. If it is desired to close the valve 20, the arm 24 is swung out of engagement with the bifurcated bracket 28, and through operation of the lever 22, the valve 20 is forced downward until seated, after which the arm 24 is allowed to swing into the bifurcated portion of the bracket 28, to the position shown in Fig. 1.

The interior of the vessel 1 is provided with a plurality of fins 29, to prevent swirling of the liquid within the vessel 1 when this liquid is agitated by the stirrer 10.

The operation of my device is as follows: The material to be treated is placed in the inner vessel 1, and the space between the vessels 1 and 2 is filled with water. The stirrer 10 is set in motion, and steam is then admitted through the perforated pipe 7 to heat the water in this water jacket and thereby heat the contents of the vessel 1. If milk is being pasteurized with my device, the steam supply is regulated by the valve 30 to hold the milk within the vessel 1 at 145° F. and for the required length of time, which is usually about thirty minutes. The hot water is then withdrawn through the valve 31 which communicates with the water jacket 40 through the drain pipe 32.

Cold brine is then circulated from the manifold 5 through the coils 4 until the liquid within the vessel 1 has reached the required temperature, generally about 38-40° F. when milk is being treated. Instead of brine, other refrigerants may be used; for example, cold water, sulphur dioxide, ammonia, etc. The temperature of the material being heated or cooled, as the case may be, in the vessel 1 is shown by the thermometers 45 19. After this pasteurizing and cooling, the liquid may be kept in the vessel 1, which thus serves as a storage tank, and the desired temperature of the treated material within the vessel 1 may be readily maintained by regulating the circulation of the refrigerant through the coils 4. If desired, the material may be withdrawn immediately after the cooling step, so that the apparatus will be available for receiving other material for treatment.

My new device combines into one receptacle the mechanism and apparatus heretofore employed and involving several devices performing their individual functions.

With my new apparatus all of the operations 65 of pasteurization, namely, heating the liquid, holding the liquid at the pasteurization temperature, and cooling are all performed in the same unit and without removal of the liquid undergoing treatment. The pasteurization is, therefore, obviously highly efficient and most economical. My device also serves as a refrigerated storage tank.

My new apparatus is adaptable to a wide variety 70 of service including the pasteurization of milk, cream, ice cream mixes, chocolate milk, butter 75 milk, especially where limited quantities are in-

volved or where the use of the regular equipment is not practical. When milk is treated, it may be placed into the vessel 1 immediately after milking, where the pasteurization and low temperature may be quickly attained and the milk can be retained therein until final disposition, with practically no rise in temperature.

The present invention is not limited to the specific details set forth in the foregoing examples which should be construed as illustrative and not by way of limitation, and in view of the numerous modifications which may be effected therein without departing from the spirit and scope of this invention, it is desired that only such limitations be imposed as are indicated in the appended claims.

I claim as my invention:

1. In a heat-interchange apparatus, an inner vessel, an outer vessel surrounding said inner vessel in spaced relation both laterally and at the bottom to said inner vessel and forming a tight jacket for said inner vessel, a plurality of hollow coils including coils having a plurality of convolutions, a manifold disposed between said vessels and in spaced relation to said inner vessel for supplying heat-exchange fluid to said coils, a manifold disposed between said vessels and in spaced relation to said inner vessel for receiving the fluid after passage through said coils, means for connecting said coils to said manifolds, means independent of said manifolds for supplying heat-exchange fluid to the space between said vessels, the convolutions of said coils being in direct contact with each other and with said inner vessel, and means comprising heat-conducting material in the interstices between the adjacent convolutions of said coils and said inner vessel and forming a direct and voidless heat-transfer union between the contents of said coils and the contents of said inner vessel.

2. In a heat-interchange apparatus, an inner vessel, an outer vessel surrounding said inner vessel in spaced relation both laterally and at the bottom to said inner vessel and forming a tight jacket for said inner vessel, a plurality of hollow coils including coils having a plurality of convolutions, a manifold disposed between said vessels and in spaced relation to said inner vessel for supplying heat-exchange fluid to said coils, a manifold disposed between said vessels and in spaced relation to said inner vessel for receiving the fluid after passage through said coils, a perforated steam pipe extending into the space between said vessels, the convolutions of said coils being in direct contact with each other and with said inner vessel, means comprising heat-conducting material in the interstices between the adjacent convolutions of said coils and said inner vessel and forming a direct and voidless heat-transfer structure between the contents of said coils and the contents of said inner vessel, and agitation means within said inner vessel.

3. In a heat-interchange apparatus, an inner vessel, an outer vessel surrounding said inner vessel in spaced relation both laterally and at the bottom to said inner vessel and forming a tight jacket for said inner vessel, a plurality of hollow coils including coils having a plurality of convolutions, a manifold disposed between said vessels and in spaced relation to said inner vessel for supplying heat-exchange fluid to said coils, a manifold disposed between said vessels and in spaced relation to said inner vessel for receiving the fluid after passage through said coils, means for connecting said coils to said

manifolds, means independent of said manifolds for supplying heat-exchange fluid to the space between said vessels, the convolutions of said coils being in direct contact with said inner vessel, and

5 means comprising heat-conducting material in the interstices between the adjacent convolutions

of said coils and said inner vessel and forming a direct and voidless heat-transfer union between the contents of said coils and the contents of said inner vessel.

ROBERT E. KAESTNER.
